(57) **CLAIM**

I claim the ornamental design for a shoe deodorizer, as shown.

DESCRIPTION

FIG. 1 is a perspective view of a shoe deodorizer comprising the present invention;

FIG. 2 is a front elevational view of the shoe deodorizer;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.
